(57) **CLAIM**

The ornamental design for a package for a medicinal product, as shown and described.

DESCRIPTION

FIG. 1 is a bottom perspective view of a package for a medicinal product showing the new design.

FIG. 2 is a bottom plan view thereof.

FIG. 3 is a top plan view thereof.

FIG. 4 is a front elevation view thereof.

FIG. 5 is a rear elevation view thereof; and,

FIG. 6 is a side view thereof.

The broken lines shown in FIGS. 1-6 represent unclaimed subject matter and form no part of the claimed design.
